UNITED STATES PATENT OFFICE.

AARON WILLIAM FRAIL, OF ASHLAND, MASSACHUSETTS.

GAS-MACHINE.

SPECIFICATION forming part of Letters Patent No. 321,959, dated July 14, 1885.

Application filed October 1, 1884. (No model.)

To all whom it may concern:

Be it known that I, AARON W. FRAIL, a citizen of the United States, residing at Ashland, in the county of Middlesex and State of Massachusetts, have invented certain new and useful Improvements in Gas-Machines; and I do hereby declare that the following is a full, clear, and exact description thereof, reference being had to the accompanying drawings, 10 making a part of this specification, and in which—

Figure 1 is a side view of my improved gas-machine, a portion of the casing being broken away to show more clearly the central part of 15 the machine. Fig. 2 is a cross-section taken at line *a a*, Fig. 1, looking in the direction of arrow *a'*, same figure. Fig. 3 is a horizontal section taken on line *b b*, looking in the direction of arrow *b'*, same figure. Fig. 4 is a view of 20 the under side of the top part of the case of the machine, showing the partitions or divisions between which the gas passes in its escape from the generating-wheel to the supply-pipe, in order to free itself from any particles of the 25 liquid gasoline with which it may be overcharged by condensation. Fig. 5 represents, on an enlarged scale, a longitudinal central section of the machine, showing the several parts in their relative positions, and Fig. 6 30 represents, on a smaller scale, a cross-section of the top part of the machine, taken on line *c c*, Fig. 3, looking in the direction of arrow *c'*, same figure, showing the inlet-pipe for the liquid gasoline and the valve mechanism for 35 regulating the supply thereof.

My invention relates to improvements in machines for the production of illuminating-gas from liquid hydrocarbon; and it consists in certain novel features of construction and novel 40 arrangement of parts, as hereinafter described and claimed.

In the drawings, *A* is the case of the machine for containing the several parts. It is made air-tight and of any suitable material 45 and size.

In the top part of the case *A* is formed a shallow pan, *B*, for containing a supply of gasoline, which runs into the pan through the inlet-pipe *d*, (see Fig. 6,) the flow of the liquid 50 being regulated by a valve, *e*, and suitable mechanism for operating the same, consisting

of a pivoted arm, *f*, and ball-float *g* of the usual construction, said float *g* resting upon the liquid gasoline contained in case *A*, as shown in Fig. 5, and being operated in the 55 usual and well-known way. From the pan *B* the gasoline runs through an opening, *h*, therein, (see Figs. 3 and 5,) upon the generating-wheel, and into the lower part of the case *A*, the amount of gasoline being regulated by 60 the float *g*, before mentioned. The cover or top part, *i*, of the case *A* is provided with partitions or divisions *j*, as shown in Fig. 4, extending down therefrom at right angles, the lower edges of the partitions *j* extending into 65 the liquid contained in the pan *B*. (See Fig. 5.) The object and purpose of these partitions *j* is to form a circuitous passage (see arrows Fig. 4) for the escape of the gas after it has been generated and escaped through the opening *h* 70 in the pan *B*, and before it passes off through the supply-pipe *k* in the top of the case *A*, the object being to separate any liquid particles with which the gas may be impregnated or overcharged, said particles dropping into the 75 pan *B*, and being used over again with the rest of the gasoline.

The generating-wheel *C* is made of two perforated or gauze cylinders, *D* and *E*, one within the other, the outer cylinder, *D*, being provided with buckets or troughs *l*, for raising the liquid gasoline contained in the case *A*, and dropping it upon the inner cylinder, *E*. The wheel *C* is secured to and revolves with the shaft *F*, which turns in suitable bearings, 80 *m*, made in one end of the case *A*, and in a recess formed in one side of the part *G*, to be hereinafter described. (See Fig. 5.) The ends of the generating-wheel *C* are made solid, the end toward the part *G* being cut out in the central part around the shaft *F*, and the cylindrical part *n*, open at one end and provided with holes *o* at the other end, is fitted therein and secured thereto, extending within the inner cylinder, *E*, about half the depth or width of 85 the wheel *C*. (See Fig. 5.)

Into the part *n* of the wheel *C* extends the circular or cylindrical part *H*, open at both ends, and formed upon the partition or division *I*, which extends through the central part 90 of case *A*, being secured therein in any suitable manner. The part *H* is a little smaller

than the part *n* of the wheel *C*, so as to allow the wheel *C* to revolve freely around it, as shown in Fig. 5.

The driving-wheel *J* is constructed in the usual and well-known manner, of tin or other suitable material, and similar to wheels for measuring gas in wet meters. It is attached to and revolves with the shaft *K*, which turns in suitable bearings, *p*, made in one end of the case *A* and in one side of the part *G*. (See Fig. 5.) On one end of the shaft *K* is secured a small gear, *q*, which meshes with a gear, *r*, secured to the shaft *F* of the generating-wheel *C*, to turn said wheel. The end *s* of the driving-wheel *J* is made solid, provided only with an opening, through which the air enters, passing through the part *G*, one side of which has a projecting part, *L*, extending within said wheel, as shown in Fig. 5. The other end, *t*, of the driving-wheel *J* is provided with flaring slots or openings, through which the air escapes after having acted on the wheel to turn the same.

The part or pipe *G*, before mentioned, is made of any suitable material, of substantially the form and construction shown in the drawings, being secured in the central part of the case *A*, in any suitable manner in the position shown. To one end of the part *G* is attached the inlet-pipe *M*, extending through the side of the case *A*, and through which the air is forced by means of any suitable blower outside of the case *A*. To the other end of the part *G* is attached the outlet or waste pipe *N*, extending through the side of case *A*, and provided with a faucet, from which the moisture condensed from the air may be drawn off. The part *G* has projecting from one side the hollow part *L*, before mentioned, which extends into the driving-wheel *J*, and around which said wheel revolves. Said part *L* has an arm or pipe, *L'*, projecting at right angles therefrom, through which the air passes to the interior of the driving-wheel *J*.

Through the central part of the arm *L* extends a hollow air-tight sleeve, *O*, (see Fig. 5,) secured to the part *G*, through which the shaft *K* of the driving-wheel *J* extends, the object of which is to allow the air to enter freely all around the part *O*, inclosing the shaft *K*. The part *G* has a depression, *u*, in one side, into which fit the gears *q* and *r*, before mentioned, and also forming bearings *m* and *p*, in which one end of the shafts *F* and *K* turns.

The special object and purpose of the part or pipe *G* is to form suitable bearings for one end of the shafts of the driving-wheel and the generating-wheel, the other end having bearings in the inner sides of the case *A*, as shown, and also to furnish in the best manner possible a means for the air to enter into the machine for the purpose of operating or putting in motion the driving-wheel, and also for becoming impregnated or charged with the gasoline in the generating cylinder or wheel.

The driving-wheel *J* and the part *G*, and the parts connected therewith, are inclosed in

a separate case formed by the partition or top *P* and the side partition, *I*, which has formed thereon the cylindrical part *H*, before mentioned, which extends into one end of the generating-wheel *C*. The partitions *P* and *I* are secured within the case *A* in any suitable manner. The partition *I* does not extend quite to the bottom of case *A*, (see Fig. 5,) so as to allow the gasoline to circulate freely in the lower part of case *A*.

The object of inclosing the driving-wheel *J*, and the part *G*, as above described, is to retain the air and allow it to escape and pass to the generating wheel or cylinder only in the direction as shown by arrows, Fig. 5.

The operation of my machine is as follows: The gasoline is first allowed to run into the lower part of the case *A*, through the inlet-pipe *d* and the opening *h* in the pan *B*, until the case *A* is about half full, as shown by dotted line *x*, Fig. 5. The valve *e*, with which the inlet-pipe *d* is provided, is then closed by the raising of the float *g*, and as the gasoline is used in the manufacture of the gas, the lowering or sinking of the float *g* opens the valve in the usual manner, allowing more gasoline to run in. The pan *B* always has gasoline in it up to the top of the opening *h*, as shown by dotted line *y*, Fig. 5. The driving-wheel *F*, when it is desired to put the machine in operation, is revolved by forcing air by means of any suitable blower into the inlet-pipe *M*, through the hollow part *G*, part *L*, and part *L'*, into the wheel *J*. (See arrows, Fig. 5.) The revolving of the wheel *J* causes the generating-wheel *C* to revolve, the outer cylinder of which, *D*, being provided with troughs or buckets *l*, as before stated, raises the gasoline contained in case *A*, and as the generating-wheel revolves this gasoline thus raised is poured out of the buckets *l* and falls back upon the inner perforated cylinder, *E*, which cylinder being hollow, without any packing or absorbent material contained therein, a mist or spray of gasoline is formed within the inner cylinder, *E*, which is taken up by the air passing from the driving-wheel *J*, as shown by arrows, Fig. 5, into the interior of said cylinder and the generating-wheel *C* through the part *H*, and the holes *o* in the part *n* of one end of said generating-wheel *C*. The air, after being impregnated or charged with gasoline within the generating-wheel *C* in the manner above described, passes out through the perforated cylinders *D* and *E*, and through the opening *h* in the pan *B*, and between the partitions or divisions *j* in the top part of the case *A* into the gas-supply pipe *k* in the top of case *A*, being evenly and perfectly carbureted before passing into said supply-pipe.

Having described my improvements in gas-machines, what I claim therein as new and of my invention, and desire to secure by Letters Patent, is—

1. The combination, with the case *A*, perforated generating-cylinders *D* and *E*, and the driving-wheel *J*, of the tubular part or pipe

G, for the purpose stated, all constructed and operated substantially as shown and described.

2. The combination, with the case A, provided with a pan, B, the top part of the case 5 A having the partitions or divisions *j*, of the perforated cylinders D and E, tubular part G, and driving-wheel J, all constructed and operated substantially as and for the purpose stated.

3. In a gas-machine, the part G, provided 10 with an inlet-pipe, M, and an outlet-pipe, N, for the purpose stated, and constructed with bearings for one end of driving-shafts, as described, and made hollow to allow of the air passing through into the driving-wheel, for the 15 purpose stated, in combination with the driv-

ing-wheel J and perforated cylinders D and E, substantially as shown, and for the purpose stated.

4. In a gas-machine, the generating-wheel C, made of two perforated or gauze cylinders, 20 D and E, the outer one being provided with lifting troughs or buckets, for the purpose stated, and means for revolving said generating-wheel, substantially as described, in combination with the tubular part G and driving-wheel J, substantially as shown and described. 25
